UNITED STATES PATENT OFFICE.

WILLIAM E. COOK, OF NEW YORK, N. Y., ASSIGNOR, BY MESNE ASSIGNMENTS, TO THE PEERLESS INSULATED WIRE AND CABLE COMPANY, OF NEW YORK, N. Y., A CORPORATION OF DELAWARE.

METHOD OR ART OF MAKING INSULATED WIRE.

1,415,151.

Specification of Letters Patent. Patented May 9, 1922.

Application filed April 24, 1917. Serial No. 164,302.

To all whom it may concern:

Be it known that I, WILLIAM E. COOK, a subject of the King of the United Kingdom of Great Britain and Ireland, residing at St. George, in the borough of Richmond, city of New York, county of Richmond, and State of New York, have invented certain new and useful Improvements in the Method or Art of Making Insulated Wire, of which the following is a specification, reference being had therein to the accompanying drawings, which form a part thereof.

My invention relates to a method or art of making insulated wires, and more particularly to improvements in the manner of producing such wire having insulation consisting of an absorbent body saturated or impregnated with asphaltum or other composition for waterproofing, and increasing the resistance of, the coating material.

Heretofore conductor wires have been produced by wrapping the wire in a cotton sliver and after compacting the sliver upon the wire forming a continuous braid about the insulating material prior to saturating, or impregnating, the sliver and the braid, with an asphaltum or similar composition. This method, as demonstrated by use, has certain disadvantages both as to the manner of producing insulating wires, and as to the finished product. In producing the wire, the incorporation of the covering braid in the structure is a separate and distinct operation from the winding of the cotton sliver about the wire. Furthermore, since the material of which the braid is formed is relatively much less absorbent than the compressed cotton sliver, the presence of the braid upon the exterior of the insulated wire has a tendency to prevent a uniform absorption of the asphaltum or other composition by the compacted cotton sliver. By my present invention, I am enabled to produce an insulated wire wherein the ordinary braid

is entirely dispensed with, the cotton sliver being held in a compact mass about the wire in a manner not to interfere with the thorough impregnation of this sliver with the viscous asphaltum or other composition, the first of the finishing operations in the production of the wire. Furthermore, the threads or cords used for binding the sliver upon the wire are applied substantially simultaneously with the sliver, allowing only

a sufficient interval to ensure a thorough compaction of the sliver before applying said threads or cords thereto. In this manner the cotton sliver and the binding threads or cords acting thereon, are incorporated in the wire by a practically continuous operation. As the thread or cord is applied to the sliver, it is imbedded in the body of the sliver to an extent to be practically invisible in the completed article, thus permitting the application of the finishing wax directly to the sliver which will readily conform to the iron during the polishing operation in a manner to produce a wire with a well formed and smooth surface.

The invention consists primarily in the herein described method or art of making insulated wire consisting in winding a cotton sliver spirally about a conductor wire, with the edges thereof overlapping, compacting said sliver upon the wire, winding a strand of flexible, absorbent material about and embedding successive convolutions thereof within said sliver while it is compacted and thereafter saturating or impregnating said sliver and said strand with a viscous composition whereby the insulating property thereof is increased, the completed wire is waterproofed and said sliver and said strand are set; and in such other novel steps and practices as are hereinafter set forth and described, and more particularly pointed out in the claims hereto appended.

Referring to the drawings,

Fig. 1 is a side elevation of the machine showing the manner of applying the cotton sliver and the binding to a conductor wire; and

Fig. 2 illustrates an apparatus used in the step of saturating or impregnating the covering for the wire with asphaltum or other viscous composition.

Like letters refer to like parts in both views.

In the practice of the method or art of my invention, a continuous strand of a conductor wire *a* is passed through a bath of adhesive material indicated at *b* and has imparted thereto, continuous traverse at a substantially uniform speed, being passed over the rollers *c* to a rewinding reel (not shown). During this traverse a continuous strip of cotton sliver *d* is spirally wound about the conductor wire *a*, the edges of succeeding

convolutions forming a lap joint so as to secure continuity of this cover and substantially the same thickness thereof throughout. This sliver is applied by means of a rotating 5 platform *e* adapted to carry a container *f* for the sliver, the wire *a* passing vertically through this platform, axially thereof. After the application of the sliver to the wire, the wire with the sliver thereon passes 10 through a compressing horn *g* having rotary movement with the platform *e*. Thereafter the wire and the partially compacted covering therefor passes from the horn *g* to a second horn *h* which still further compacts said 15 sliver. Immediately after the wire and its covering passes from the horn *h*, it passes through a rotating frame *i* having mounted therein one or more spools *j* containing a flexible strand *j* of absorbent material, such 20 as cotton thread, or cord which is continuously rotated so as to wind said thread, or cord spirally about the cotton sliver. This thread, or cord is subjected to tensioning stresses in any desired manner, so as to cause 25 it to tightly embrace the cotton sliver and be firmly imbedded therein.

By applying the confining thread or cord immediately following the final compression of the cotton sliver, the desired density of 30 this covering material is secured.

Preferably a plurality of independent parallel strands are used, to permit the use of a fairly wide sliver confined at a number of different points by the thread or cord.

35 When the frame *i* is carried by and rotated at the same speed as, the table *e*, the spiral convolutions of the thread or cord will have the same pitch as and conform to those of the cotton sliver.

40 After the cotton sliver has been applied to the wire, and confined in position by the spirally wound strand, or strands, of thread or cord, the wire with its covering is passed through a tank *k* containing a mass of viscous insulating, adhesive and waterproof material, such as the asphaltum composition ordinarily used in making insulated wires. The wire after the setting of this composition 45 is waxed and passed through polishing and finishing irons giving the desired, and final finish thereto.

By reason of the application of adhesive to the wire before wrapping the sliver spirally thereupon, this sliver will be firmly 55 bonded to the wire, so as to resist displacement by the compression horns even though these horns do not have rotary movement.

While the covered wire is in the asphaltum or other similar bath, the cotton sliver will 60 readily absorb this composition by reason of the fact that substantial areas of the cotton sliver project between the strands of thread or cord, which as heretofore stated, are imbedded well within the sliver, the portions of the sliver between said strands form-

ing ducts through which the composition may readily flow to the bottom of the sliver.

The compression of the sliver will matte the fibers thereof, the thread or cord preventing expansion after compression; and 70 the application of the asphaltum or other composition causes the fibers to firmly adhere or set, and at the same time firmly bonds the thread or cord to the sliver.

In the finished product the binding threads 75 or cords will not be perceptible as the cotton sliver will ordinarily lap thereover in a manner to completely conceal same.

Preferably, to permit the operation of the machine used at high speed, I employ a cotton sliver having imbedded therein and bonded thereto, a continuous cotton thread or cord which will serve to supplement the action of the binding threads or cords applied to the exterior of the sliver, in holding 85 the sliver in its compacted condition upon the wire.

In this manner, I am enabled by a substantially simultaneous or continuous operation, to apply both the cotton sliver and the 90 binding thread or cord to the wire thereby gaining the advantage over the present methods of avoiding the necessity for passing the wires successively through a machine for wrapping the sliver about the wire, and 95 a machine for applying the cover thereto.

Having described the invention what I claim as new and desire to have protected by Letters Patent is:—

1. The herein described method or art of 100 making insulated wire consisting in winding a cotton sliver spirally about a conductor wire with the edges thereof overlapping, compacting said sliver upon the wire, winding a strand of flexible, absorbent material 105 about and embedding successive convolutions thereof within said sliver while it is compacted, the convolutions of said strand being spaced apart to form ducts therebetween to facilitate the penetration of a viscous composition throughout the body of 110 said sliver, and thereafter saturating or impregnating said sliver and said strand with a viscous composition, whereby its insulating property is increased, the completed 115 wire is waterproofed and the fibers of said sliver and said strand are bonded together.

2. The herein described method or art of 120 making insulated wire consisting in winding a cotton sliver spirally about a conductor wire with the edges thereof overlapping, compacting said sliver upon the wire, winding a strand of flexible, absorbent material 125 spirally about and embedding successive convolutions thereof within said sliver while it is compacted, and at the same pitch at which said sliver is wound, the convolutions of said strand being spaced apart to form ducts therebetween to facilitate the penetration of a viscous composition throughout the 130

body of said sliver and thereafter saturating or impregnating said sliver and said strand with a viscous composition, whereby its insulating property is increased, the completed 5 wire is waterproofed and the fibers of said sliver and said strand are bonded together.

3. The herein described method or art of making insulated wire consisting in winding a cotton sliver spirally about a conductor wire with the edges thereof overlapping, compacting said sliver upon the wire, winding a strand of flexible, absorbent material spirally about said sliver while it is compacted, and at the same pitch at which said 10 sliver is wound, said strand being tensioned while being wound to imbed it in said sliver, succeeding convolutions of said strand being spaced apart to form ducts to facilitate the penetration of a viscous composition 15 throughout the body of said sliver and thereafter saturating or impregnating said sliver and said strand with a viscous composition, whereby its insulating property is increased, the completed wire is waterproofed and the fibers of said sliver and said 20 strand are bonded together.

4. The herein described method or art of making insulated wire consisting in winding a cotton sliver spirally about a conductor 25 wire with the edges thereof overlapping, compacting said sliver upon the wire, winding a plurality of strands of flexible, absorbent material about and embedding successive convolutions thereof within said sliver while 30 it is compacted, said strands being laid in parallel lines spaced apart to form ducts to facilitate the penetration of a viscous composition throughout the body of said sliver, and thereafter saturating or impregnating 35 said sliver and said strands with a viscous composition, whereby the insulating property is increased, the completed wire is waterproofed and the fibers of said sliver and said strands are bonded together.

45 5. The herein described method or art of making insulated wire consisting in winding

a cotton sliver spirally about a conductor wire with the edges thereof overlapping, compacting said sliver upon the wire, winding a plurality of strands of flexible, absorbent material about said sliver while it is compacted, and at the same pitch at which said sliver is wound, said strands being tensioned while being wound to imbed them in said sliver, said strands being laid in parallel lines spaced apart to form ducts to facilitate the penetration of a viscous composition throughout the body of said sliver, and thereafter saturating or impregnating said sliver and said strand with a viscous composition, whereby the insulating property is increased, the completed wire is waterproofed and the fibers of said sliver and said strands are bonded together.

6. The herein described method or art of making insulated wire consisting in winding a cotton sliver spirally about a conductor wire with the edges thereof overlapping, compacting said sliver upon the wire, winding a plurality of strands of flexible, absorbent material spirally about said sliver while it is compacted, said strands being laid in substantially parallel lines spaced apart to form ducts to facilitate the penetration of a viscous composition throughout the body of said sliver, maintaining said strands under tension while winding them, to imbed them in the sliver, and thereafter saturating or impregnating said sliver and said strands with a viscous composition, whereby the insulating property is increased, the completed wire is waterproofed and the fibers of said sliver and said strands are bonded together.

In witness whereof, I hereunto affix my signature in the presence of two subscribing witnesses, this 9th day of April, 1917.

WILLIAM E. COOK.
